UNITED STATES PATENT OFFICE.

WILLIAM P. BETTENDORF, OF DAVENPORT, IOWA.

TANK-CAR.

SPECIFICATION forming part of Letters Patent No. 788,016, dated April 25, 1905.

Application filed March 30, 1904. Serial No. 200,830.

To all whom it may concern:

Be it known that I, WILLIAM P. BETTENDORF, a citizen of the United States, and a resident of Davenport, in the county of Scott and State of Iowa, have invented certain new and useful Improvements in Tank-Cars, of which the following is a full, clear, and exact description.

Tank-cars now in use are so constructed that the draft-rigging and the line of draft therethrough are below the tank. Considering the side wash of the oil or other liquid contents of the tank while the car is in motion, the danger of the car turning over because of the great centrifugal force when rounding curves or jumping the tracks is a source of anxiety to railroad men.

The object of my invention is to so construct the car as to lower the center of gravity of the tank, and thus minimize this danger. This I accomplish by the means hereinafter fully described, and as particularly pointed out in the claims.

In the drawings, Figure 1 is a longitudinal central section of a tank-car embodying my invention. Fig. 2 is a longitudinal central section of one of the said tank-cars, drawn to a larger scale and taken on dotted line 2 2, Fig. 3, looking in the direction indicated by the arrows. Fig. 3 is an end view of the lower portion of one end of the tank, drawn to a still larger scale. Fig. 4 is a transverse section taken on dotted line 4 4, Fig. 2, looking in the direction indicated by the arrows, but on a slightly larger scale. Fig. 5 is a plan view of the under side of the tank, illustrating the manner in which it is prepared to receive my improvements. Fig. 6 is an end view of the same. Fig. 7 is a transverse section of the tank, illustrating a modified construction of the buffer-column.

Referring to the drawings, A represents a suitable tank which is provided with a longitudinally-elongated rectangular opening *a* in each end, which extends from an opening *b* of about the same width in the heads thereof back therefrom past the transverse plane of the truck-pivot. Placed in these openings *a b* is an inverted - channel - shaped draft - rigging

frame B, which is preferably cast in one piece 50 of metal and has its lower longitudinal edges provided with lateral flanges *c c*, that lap against the under side of the shell of the tank adjacent to said opening and are riveted or otherwise securely fastened thereto. The forward ends of the rigging-frame B, which extend through opening *b* in the tank, are also provided with lateral flanges that form a shield C, which is riveted or otherwise suitably secured to the outer surface of the head of the 60 tank and greatly strengthens and reinforces the same. The end *x* of the channeled portion of the rigging-frame opposite the shield C terminates just before it reaches the center plate and is closed, and between this closed end *x* 65 and the head of the tank said frame is provided on its vertical sides with inwardly-projecting vertical stops *dd*, that are engaged by the follower-plates *ee* of the draw-bar D, which latter is supported by a U-shaped carry-iron 70 *f* at the entrance of the channel of the rigging-frame and under the yoke thereof by a suitable cross-frame E, whose downturned side edges are bolted or riveted to the sides of the channel of frame B, which latter has its lower 75 edges dropped slightly at this point.

The rigging-frame B extends back from its closed end *x* in a plane corresponding to that of the shell of the tank, and this extension *g* passes over the truck-bolster and has the body 80 center-plate *g'* suitably secured to the under side thereof. The rear edge of this extension has cast in one piece therewith and arising therefrom a buffering-head F, consisting, preferably, of a solid block of metal of about the 85 same height and width as the channeled portion of the rigging-frame, to which it is connected by a centrally-located longitudinally-disposed vertical web *h*. The vertical side of this head farthest from the channeled portion 90 of frame B is provided with a longitudinal central opening, and secured in the opening of the head F of the draft-rigging frame at each end of the tank is a tubular buffering-column. The office of this buffering-column is to 95 take up the strain of the pull of the draw-bar and the shock of the bumping of the cars and to relieve the shell of the tank therefrom and

in addition to serve as a steam-chamber to keep the liquid contents of the tank warm, particularly in cold weather. Steam is introduced into column G through vertical inlet-ports H, made in said heads F, to the lower ends of which suitable steam-pipes J are connected, substantially as shown. The buffing-column is preferably of such dimensions that the necessity for the presence of other steam-pipes in the tank is dispensed with, and it forms a continuous connection between the draft-rigging frame and practically takes the place of center sills. If desired, the buffing-column could between the heads F be provided with a series of looped pipe connections I, whose ends, spider fashion, would radiate therefrom and which between their ends would run substantially parallel with said column. Such an arrangement of steam-pipes might be deemed desirable in cold climates; but I do not desire to be confined to their use nor to the exact location of the buffing-column as shown.

In the construction of my improved car the connections between the draft-rigging frame B and the tank A are made as tight as possible to prevent the leakage of the contents of the car. Such leakage may be further guarded against by partitioning off the lower portion of the ends of the tank in which the draft-rigging frames are secured, so that an empty chamber surrounds the same. This I accomplish by a sheet-metal cover K, that arches over the rigging-frame B, as shown in Figs. 2 and 4 of the drawings, and has its end farthest from the head of the tank bent vertically down and clamped against the adjacent vertical surface of the buffing-head F by the circumferential flange L, projecting from the buffing-column near their ends. The edges of this cover K bearing against the inner surface of the head of the tank, the longitudinal edges of said cover, and the transverse edges of the end of the same contiguous to the buffing-head are all flanged and riveted or otherwise suitably secured to the shell of said tank. The construction of the draft-rigging frame may be modified to suit the type or style of draft-rigging set forth in the specifications of the purchaser and may be so designed and made as to allow the horizontal plane of said frame to be relatively higher or lower in said tank than as shown. All such changes I desire to be considered as contemplated within the spirit of my invention, the object of which, briefly stated, is to lower the center of gravity of the tank, and by thus reducing the height of the triangle, of which the center of gravity is the apex and the ball of the rails of the track the lower angles, broaden the base upon which the car is supported and give greater stability to the same when in motion.

What I claim as new is—

1. A tank-car comprising a tank extending

from end to end of the car over the trucks, 65 with the bottom thereof in the same plane from end to end and with the major part of the circumference thereof above the line of draft, and draft-rigging embedded in each end of the same whose line of draft is within the 70 circumference of said tank and above the plane of the bottom of the liquid contents thereof.

2. A tank-car comprising a tank extending from end to end of the car over the trucks, 75 with the bottom thereof in the same plane from end to end and with the major part of the circumference thereof above the line of draft, and draft-rigging the line of draft of which is within the circumference of said tank 80 and above the plane of the bottom of the liquid contents thereof.

3. A tank-car comprising a tank extending from end to end of the car over the trucks, 85 with the bottom thereof in the same plane from end to end and with the major part of the circumference thereof above the line of draft, draft-rigging embedded in each end thereof, and a longitudinally-disposed buffer-column connecting said rigging above the 90 plane of the bottom of the liquid contents thereof.

4. A tank-car comprising a tank extending from end to end of the car over the trucks, 95 with the bottom thereof in the same plane from end to end and with the major part of the circumference thereof above the line of draft, draft-rigging embedded in each end thereof, and a longitudinally-disposed tubular buffer-column connecting said rigging above 100 the plane of the bottom of the liquid contents thereof.

5. A tank-car comprising a tank extending from end to end of the car over the trucks, 105 with the bottom thereof in the same plane from end to end and with the major part of the circumference thereof above the line of draft, draft-rigging embedded in the ends thereof, and a longitudinally-disposed buffer-column located within the circumference of 110 said tank and connecting said draft-rigging above the plane of the bottom of the liquid contents thereof.

6. A tank-car comprising a tank extending from end to end of the car over the trucks, 115 with the bottom thereof in the same plane from end to end and with the major part of the circumference thereof above the line of draft, draft-rigging embedded in the ends 120 thereof, and a longitudinally-disposed tubular buffer-column connecting said draft-rigging and located within the circumference of said tank above the plane of the bottom of the liquid contents thereof.

7. A tank-car comprising a tank, draft-rigging embedded in the ends thereof, a longitudinally-disposed tubular buffer-column within said tank connecting said draft-rigging, and

- steam connections communicating with said column.
8. A tank-car comprising a tank extending from end to end of the car over the trucks, with the bottom thereof in the same plane from end to end and with the major part of the circumference thereof above the line of draft, draft-rigging embedded in each end thereof, and means independent of said tank connecting the same above the plane of the bottom of the liquid contents of said tank.
9. A tank-car comprising a tank extending from end to end of the car over the trucks, with the bottom thereof in the same plane from end to end and with the major part of the circumference thereof above the line of draft, draft-rigging embedded in each end thereof, the line of draft of which is within the circumference of said tank, and means alining with said line of draft and connecting said draft-riggings above the plane of the bottom of the liquid contents of said tank.
10. A tank-car comprising a tank having a longitudinally-elongated opening in the under side of each end thereof, and draft-riggings secured within and closing said openings.
11. A tank-car comprising a tank having a longitudinally-elongated opening in the under side of each end thereof, and integral draft-riggings secured within and closing said openings.
12. A tank-car comprising a tank having a longitudinally-elongated opening in the under side of each end thereof, and draft-riggings cast in one piece of metal and secured within and closing said openings.
13. A tank-car comprising a tank having a longitudinally-elongated opening in the under side of each end thereof, and draft-riggings secured within and closing said openings, the line of draft of which comes within the circumference of said tank.
14. A tank-car comprising a tank having a longitudinally-elongated opening in the under side of each end thereof, and integral draft-riggings secured within and closing said openings, the line of draft of which comes within the circumference of said tank.
15. A tank-car comprising a tank having a longitudinally-elongated opening in the under side of each end thereof, and draft-riggings cast in one piece of metal and secured within and closing said openings; the line of draft of which comes within the circumference of said tank.
16. A tank-car comprising a tank having a longitudinally-elongated opening in the under side of each end thereof, draft-riggings secured within and closing said openings, and means independent of the said tank connecting said draft-rigging.
17. A tank-car comprising a tank having a longitudinally-elongated opening in the under side of each end thereof, integral draft-riggings secured within and closing said openings, and means independent of the said tank connecting said draft-rigging.
18. A tank-car comprising a tank having a longitudinally-elongated opening in the under side of each end thereof, draft-riggings cast in one piece of metal and secured within and closing said openings, and means independent of the said tank connecting said draft-rigging.
19. A tank-car comprising a tank having a longitudinally-elongated opening in the under side of each end thereof, draft-rigging secured within and closing said openings, and a longitudinally-disposed buffer-column connecting said rigging.
20. A tank-car comprising a tank having a longitudinally-elongated opening in the under side of each end thereof, draft-riggings secured within and closing said openings, and a longitudinally-disposed tubular buffer-column connecting said rigging.
21. A tank-car comprising a tank having a longitudinally-elongated opening in the under side of each end thereof, draft-rigging secured within and closing said openings, and a longitudinally-disposed buffer-column connecting said rigging and located within the circumference of said tank.
22. A tank-car comprising a tank and draft-rigging comprising an imperforate inverted-channel-shaped structure which is cast in one piece and embedded in each end of said tank.
23. A tank-car comprising a tank and draft-rigging comprising an imperforate inverted-channel-shaped structure which is cast in one piece and embedded in each end of said tank the line of draft of which is within the circumference of said tank.
24. A tank-car comprising a tank, draft-rigging comprising an imperforate inverted-channel-shaped structure which is cast in one piece and embedded in each end of said tank, and a longitudinally-disposed buffer-column connecting said rigging.
25. A tank-car comprising a tank, draft-rigging comprising an imperforate inverted-channel-shaped structure which is cast in one piece and embedded in each end of said tank the line of draft of which is within the circumference of said tank, and a longitudinally-disposed buffer-column connecting said rigging.
26. A tank-car comprising a tank, draft-rigging cast in one piece and embedded in each end of said tank, and a longitudinally-disposed tubular buffer-column connecting said rigging.
27. A tank-car comprising a tank, draft-rigging comprising an imperforate inverted-channel-shaped structure which is cast in one piece and embedded in each end of said tank the line of draft of which is within the circumference of said tank, and a longitudinally-dis-

posed tubular buffer-column connecting said rigging.

28. A tank-car comprising a tank, draft-rigging comprising an imperforate inverted-channel-shaped structure which is cast in one piece and embedded in each end of said tank, and a longitudinally-disposed buffer-column connecting said rigging within the circumference of said tank.

29. A tank-car comprising a tank, draft-rigging comprising an imperforate inverted-channel-shaped structure which is cast in one piece and embedded in each end of said tank the line of draft of which is within the circumference of said tank, and a longitudinally-disposed buffer-column connecting said rigging within the circumference of said tank.

30. A tank-car comprising a tank, draft-rigging comprising an imperforate inverted-channel-shaped structure which is cast in one piece and embedded in each end of said tank, and a longitudinally-disposed tubular buffer-column connecting said rigging within the circumference of said tank.

31. A tank-car comprising a tank, draft-rigging comprising an imperforate inverted-channel-shaped structure which is cast in one piece and embedded in each end of said tank the line of draft of which is within the circumference of said tank, and a longitudinally-disposed tubular buffer-column connecting said rigging within the circumference of said tank.

32. A tank-car comprising a tank and draft-rigging cast in one piece and embedded in each end of said tank and extending from the end of the car past the transverse plane of the adjacent truck-bearings.

33. A tank-car comprising a tank and draft-rigging cast in one piece and embedded in each end of said tank the line of draft of which is within the circumference of said tank, and extending from the end of the car past the transverse plane of the adjacent truck-bearings.

34. A tank-car comprising a tank, draft-rigging cast in one piece and embedded in each end of said tank and extending from the end of the car past the transverse plane of the adjacent truck-bearings, and a longitudinally-disposed buffer-column connecting said rigging.

35. A tank-car comprising a tank, draft-rigging cast in one piece and embedded in each end of said tank the line of draft of which is within the circumference of said tank, and extending from the end of the car past the transverse plane of the adjacent truck-bearing, and a longitudinally-disposed buffer-column connecting said rigging.

36. A tank-car comprising a tank, draft-rigging cast in one piece and embedded in each end of said tank and extending from the end of the car past the transverse plane of the adjacent truck-bearing, and a longitudinally-disposed tubular buffer-column connecting said rigging.

37. A tank-car comprising a tank, draft-rigging cast in one piece and embedded in each end of said tank the line of draft of which is within the circumference of said tank and extending from the end of the car past the transverse plane of the adjacent truck-bearing, and a longitudinally-disposed tubular buffer-column connecting said rigging.

38. A tank-car comprising a tank, draft-rigging cast in one piece and embedded in each end of said tank and extending from the end of the car past the transverse plane of the adjacent truck-bearing and a longitudinally-disposed buffer-column connecting said rigging within the circumference of said tank.

39. A tank-car comprising a tank, draft-rigging cast in one piece and embedded in each end of said tank the line of draft of which is within the circumference of said tank and extending from the end of the car past the transverse plane of the adjacent truck-bearing, and a longitudinally-disposed buffer-column connecting said rigging within the circumference of said tank.

40. A tank-car comprising a tank, draft-rigging cast in one piece and embedded in each end of said tank, and extending from the end of the car past the transverse plane of the adjacent truck-bearing, and a longitudinally-disposed tubular buffer-column connecting said rigging within the circumference of said tank.

41. A tank-car comprising a tank having a longitudinally-elongated opening in the under side of each end thereof, and a draft-rigging cast in one piece and secured within and closing said openings.

42. A tank-car comprising a tank having a longitudinally-elongated opening in the under side of each end thereof, and a draft-rigging cast in one piece and secured within and closing said openings and extending from the end of the car past the transverse plane of the adjacent truck-bearing.

43. A tank-car comprising a tank having a longitudinally-elongated opening in the under side of each end thereof, draft-rigging cast in one piece and secured within and closing said openings the line of draft of which is within the circumference of said tank.

44. A tank-car comprising a tank having a longitudinally-elongated opening in the under side of each end thereof draft-rigging cast in one piece and secured within and closing said openings, and a longitudinally-disposed buffer-column connecting said rigging.

45. A tank-car comprising a tank having a longitudinally-elongated opening in the under side of each end thereof draft-rigging cast in one piece and secured within and closing said openings, and a longitudinally-disposed tubular buffer-column connecting said riggings.

46. A tank-car comprising a tank having a longitudinally-elongated opening in the under side of each end thereof draft-rigging cast in

one piece and secured within and closing said openings the line of draft of which is within the circumference of the said tank, and a longitudinally-disposed buffer-column connecting said riggings.

47. A tank-car comprising a tank having a longitudinally-elongated opening in the under side of each end thereof, draft-rigging cast in one piece and secured within and closing said openings, and a longitudinally-disposed buffer-column connecting said riggings within the circumference of said tank.

48. A tank-car comprising a tank having a longitudinally-elongated opening in the under side of each end thereof, draft-rigging cast in one piece and secured in and closing said openings, and a longitudinally-disposed tubular buffer-column connecting said draft-rigging.

49. A tank-car comprising a tank having a longitudinally-elongated opening in the under side of each end thereof, draft-rigging cast in one piece and secured in and closing said openings, and a longitudinally-disposed tubular buffer-column connecting said draft-rigging within the circumference of said tank.

50. A tank-car comprising a tank, draft-rigging embedded in each end thereof, a longitudinally-disposed buffer-column connecting said rigging above the plane of the bottom of the liquid contents of said tank, and means within said tank covering over said draft-rigging.

51. A tank-car comprising a tank having a longitudinally-elongated opening in the under side of each end thereof, draft-rigging secured within and closing said openings, and means within said tank covering over said draft-rigging.

52. A tank-car comprising a tank having chambers made in the under side thereof adjacent to each end, and draft-rigging embedded in said tank in the bottom of the shell of the same below said chambers.

53. A tank-car comprising a tank having a longitudinally-elongated opening in the under side of each end thereof, draft-rigging secured with and closing said openings and provided with a buffer-head at the end thereof farthest from the adjacent head of the tank, and a buffer-column interposed between the buffer-heads of the draft-rigging at each end of the tank.

54. A tank-car comprising a tank having a longitudinally-elongated opening in the under side of each end thereof, draft-rigging secured within and closing said openings and provided with a buffer-head at the end thereof farthest from the adjacent head of the tank inclosed within said tank, and a buffer-column interposed between the buffer-heads of the draft-rigging at each end of the tank.

55. A tank-car comprising a tank having a longitudinally-elongated opening in the under side of each end thereof, draft-rigging se-

cured within and closing said openings and provided with a buffer-head at the end thereof farthest from the adjacent head of the tank inclosed within said tank, and a tubular buffer-column interposed between the buffer-heads of the draft-rigging at each end of the tank.

56. A tank-car comprising a tank having a longitudinally-elongated opening in the under side of each end, draft-rigging cast in one piece of metal secured within and closing said openings and having integral buffer-heads at the ends thereof farthest from the adjacent head of the tank, and a buffer-column connecting said buffer-heads.

57. A tank-car comprising a tank having a longitudinally-elongated opening in the under side of each end thereof, draft-rigging secured within and closing said openings, and a tubular buffer-column connecting said buffer-heads, which latter are provided with steam-inlet ports communicating with the bore of said buffer-column.

58. A tank-car comprising a tank, draft-rigging-frames at each end thereof, and a longitudinally-disposed buffer-column connecting said draft-rigging frames.

59. A tank-car comprising a tank having a longitudinally-elongated opening in the under side of each end thereof, channel-shaped draft-rigging frames cast in one piece of metal and secured in and closing said openings.

60. A tank-car comprising a tank having a longitudinally-elongated opening in the under side of each end thereof, and cast-metal channel-shaped draft-rigging frames having their ends farthest from the adjacent heads of said tank extended over the body center-plates of the tank.

61. A tank-car comprising a tank having a longitudinally-elongated opening in the under side of each end thereof, and cast-metal channel-shaped draft-rigging frames having their ends farthest from the adjacent heads of said tank extended over the body center-plates of the tank and terminating in buffer-heads, and a buffer-column connecting said buffer-heads.

62. A tank-car comprising a tank, an imperforate inverted channel-shaped draft-rigging frame at each end thereof, the line of draft which is above the bottom of the liquid contents of the tank extending from the end of said tank over the truck-bolster of said car, and body center-plates connected directly to said frames.

63. A tank-car comprising a tank, an imperforate inverted channel-shaped draft-rigging frame at each end thereof cast in one piece of metal and the line of draft which is above the bottom of the liquid contents of the tank extending from the end of said tank over the truck-bolster of said car, and body center-plates connected directly to said frames.

64. A tank-car comprising a tank, a chan-

- 6 neled draft-rigging at each end thereof having an extension extending beyond said channeled portion over the truck-bolster of said car whose line of draft is above the bottom of the 5 liquid contents of the tank, and body center-plates secured direct to said extension.
65. A tank-car comprising a tank, a channeled draft-rigging at each end thereof cast in one piece of metal and having an integral 10 extension extending beyond said channeled portion over the truck-bolster of said car whose line of draft is above the bottom of the liquid contents of the tank, and body center-plates secured direct to said extension.
- 15 66. A tank-car comprising a tank, a channeled draft-rigging at each end thereof having an extension extending beyond said channeled portion over the truck-bolster of said car, and buffer-heads connected with and arising 20 from the end of said extensions farthest from the said channeled portion, a longitudinally-disposed buffer-column connecting said buffer-heads, and a body center-plate connected to said extension between said buffer-heads 25 and the channeled portions of said rigging.
67. A tank-car comprising a tank, a draft-rigging frame at each end thereof extending from the end of said tank over the truck-bolster of said car, body center-plates connected 30 directly to said frames, and a longitudinally-disposed buffer-column connecting said frames.
- 35 68. A tank-car comprising a tank, a draft-rigging frame at each end thereof cast in one piece of metal and extending from the end of said tank over the truck-bolster of said car, body center-plates connected directly to said frames, and a longitudinally-disposed buffer-column connecting said frames.
- 40 69. A tank-car comprising a tank, a channeled draft-rigging at each end thereof having an extension extending beyond said channeled portion over the truck-bolster of said car, body center-plates secured direct to said 45 extension, and a longitudinally-disposed buffer-column connecting said draft-rigging.
70. A tank-car comprising a tank, a channeled draft-rigging at each end thereof cast in one piece of metal and having an integral 50 extension extending beyond said channeled portion over the truck-bolster of said car, body center-plates secured direct to said extension, and a longitudinally-disposed buffer-column connecting said draft-rigging.
- 55 71. A tank-car comprising a tank, a channeled draft-rigging at each end thereof having an extension extending beyond said channeled portion over the truck-bolster of said car, and buffer-heads connected with and arising 60 from the end of said extensions farthest from the said channeled portion, a longitudinally-disposed tubular buffer-column connecting said buffer-heads within said tank, and a body center-plate connected to said extension
- between said buffer-heads and the channeled 65 portions of said rigging.
72. A tank-car comprising a tank, a draft-rigging frame embedded in each end thereof extending from the end of said tank over the truck-bolster of said car, and body center-plates connected directly to said frames.
73. A tank-car comprising a tank, a draft-rigging frame embedded in each end thereof cast in one piece of metal and extending from the end of said tank over the truck-bolster of 75 said car, and body center-plates connected directly to said frames.
74. A tank-car comprising a tank, a channeled draft-rigging embedded in each end thereof having an extension extending beyond 80 said channeled portion over the truck-bolster of said car, and body center-plates secured direct to said extension.
75. A tank-car comprising a tank, a channeled draft-rigging embedded in each end thereof cast in one piece of metal and having an integral extension extending beyond 85 said channeled portion over the truck-bolster of said car, and body center-plates secured direct to said extension.
76. A tank-car comprising a tank, a channeled draft-rigging embedded in each end thereof having an extension extending beyond 90 said channeled portion over the truck-bolster of said car, and buffer-heads connected with and arising from the end of said extensions farthest from the said channeled portion, a longitudinally-disposed buffer-column connecting said buffer-heads, and a body center-plate connected to said extension between said 95 buffer-heads and the channeled portions of said rigging.
- 100 77. A tank-car comprising a tank, a draft-rigging frame embedded in each end thereof extending from the end of said tank over the truck-bolster of said car, body center-plates connected directly to said frames, and a longitudinally-disposed buffer-column connecting said frames.
- 105 78. A tank-car comprising a tank, a draft-rigging frame embedded in each end thereof cast in one piece of metal and extending from the end of said tank over the truck-bolster of said car, body center-plates connected directly 110 to said frames, and a longitudinally-disposed buffer-column connecting said frames.
- 115 79. A tank-car comprising a tank, a channeled draft-rigging embedded in each end thereof having an extension extending beyond 120 said channeled portion over the truck-bolster of said car, body center-plates secured direct to said extension, and a longitudinally-disposed buffer-column connecting said draft-rigging.
- 125 80. A tank-car comprising a tank, a channeled draft-rigging embedded in each end thereof cast in one piece of metal and having an integral extension extending beyond said

channeled portion over the truck - bolster of said car, body center-plates secured direct to said extension, and a longitudinally-disposed buffer-column connecting said draft-rigging.

- 5 81. A tank-car comprising a tank, a channeled draft - rigging embedded in each end thereof having an extension extending beyond said channeled portion over the truck-bolster of said car, and buffer-heads connected with
10 and arising from the end of said extensions farthest from the said channeled portion, a

longitudinally-disposed tubular buffer-column connecting said buffer-heads within said tank, and a body center-plate connected to said extension between said buffer-heads and the 15 channeled portions of said rigging.

In testimony whereof I have hereunto set my hand this 25th day of March, 1904.

WILLIAM P. BETTENDORF.
